UNITED STATES PATENT OFFICE.

GEORGE W. CAMPBELL, OF NEW YORK, N. Y., ASSIGNOR, BY MESNE ASSIGNMENTS, TO
VICTOR TYPEWRITER COMPANY.

TYPE-WRITING MACHINE.

1,114,226.

Specification of Letters Patent. Patented Oct. 20, 1914.

Application filed November 16, 1906. Serial No. 343,725.

To all whom it may concern:

Be it known that I, GEORGE W. CAMPBELL, a citizen of the United States, and resident of the borough of Manhattan, city and State of New York, have invented certain new and useful Improvements in Type-Writing Machines, of which the following is a specification.

My invention relates to typewriting machines, and is especially concerned with a novel form of ribbon movement mechanism.

The ribbon mechanism forming the subject matter of my present invention is adapted to be used in various forms of typewriters but more especially it is applicable to those machines commonly known as front strike machines in which the writing is visible and in which therefore the ribbon must be moved up into operative position as each type-bar is swung or otherwise caused to move into the striking position, and then returned to inoperative position in order to leave the writing visible.

In the ordinary form of ribbon mechanism, the ribbon is fed transversely of the machine in a horizontal direction, and it is desirable to have the ribbon as narrow as working considerations will permit, for the sake of visibility. There is therefore the danger in moving the ribbon up and down that the type, which always has greater height than breadth, will strike on the edge of the ribbon, especially in polychrome ribbons where the portion of the strip occupied by each color is necessarily narrow. This danger is further increased by the necessity of writing in more than one platen position and by the use of characters of exceptional height, as is obvious.

One object of my invention is to avoid the liability, above referred to, of the type striking on the edge of the ribbon and thus making an imperfect impression. I accomplish this object by a novel arrangement of the ribbon guides, whereby the ribbon is fed vertically through the operative field, but at the same time is fed horizontally from one side of the machine across to the other. In this way the danger of the type striking the edge of the ribbon is entirely done away with, since the movement of the ribbon frisket is in a direction longitudinal of that portion of the ribbon which is in the operative field, and therefore any inaccuracy

of the frisket movement may be neglected. 55 This ribbon guide is adapted to be used with either a single colored ribbon or a ribbon of several colors.

Other objects of my invention are to enable the use of the entire surface of the ribbon especially in the case of single colored ribbon; to obtain a better frisket movement; and to enable the throwing out of operation of the ribbon to permit the typewriter to be used for work where the type are to make 65 direct impressions, as in mimeographic work, instead of impressions through the ribbon.

These objects and advantages, together with others which will hereinafter appear, are obtained by the apparatus which I shall 70 now especially describe.

For the purpose of clearly setting forth my invention, I shall refer in its description to the accompanying drawings, which form a part of this specification, and in which, 75

Figure 1 is a rear view of the device, the ribbon being omitted for the sake of clearness, Fig. 2 is a cross section of the same taken on the line *a—b* of Fig. 1, Fig. 3 is a top plan view of the same. Fig. 4 is a 80 front view of a typewriting machine showing the device in connection with the usual form of feeding mechanism. Fig. 5 is a cross section of a detail taken on the line *a—y* in Fig. 1. 85

Referring now more specifically to said drawing, 1 is a ribbon carrier or frisket, preferably having parallel sides and carrying the guide hooks 2 and 3 through which the ribbon 4 of any suitable kind is led. The 90 guide hooks 2 and 3 are arranged one above the other and are so shaped that the ribbon enters horizontally, passes in a vertical direction from one guide hook to the other, and leaves in a horizontal direction. The 95 upper guide 3, as will be seen in Figs. 2 and 3, is also inclined toward the front of the machine, thus turning the ribbon as it passes from said guide to the side of the machine edgewise away from the plane of 100 its vertical or printing portion. This presents the upper horizontal run of the ribbon edgewise to the view of the operator, as is apparent from Fig. 4, and thus prevents this portion of the ribbon from obscuring the writing. To enable the ribbon to be moved into and out of operative position, the frisket 1 is movably positioned in

a guide frame 5, which has a pair of upwardly extending arms bearing at their ends grooved guide lugs 17, in the grooves of which the sides of the frisket 1 slide. Secured rigidly to the lower portion of the frisket 1, and passing through a guide eye 7 of the frame 5, is an operating pin 6, which prevents the frisket 1 from getting out of vertical alinement and, when reciprocated, moves it into and out of operative position. The striking point is diagrammatically indicated at 8 in Fig. 4 for the sake of clearness.

It is evident that the above arrangement of the ribbon moving mechanism, in which the operative field of the ribbon is moved up and down longitudinally, entirely does away with the danger of the ribbon being overthrown or underthrown with respect to the striking or printing point of the type on account of its narrow width, as is the case where the operative field of the ribbon is horizontally disposed and is moved widthwise up and down at each impression.

For the purpose of giving to the operating pin 6 the reciprocation by which it operates the frisket 1, the lower end of the said pin is provided with a hook 9, adapted to receive a pin 10 which projects sidewise from the end of a lever 11, fulcrumed on a cross-bar 12 journaled in a frame 13. The frame 13 is secured to the main supporting plate 14 by screws 15 and 16, extending rearwardly of the typewriter machine, frame 13 and serving to carry the whole ink ribbon guiding and shifting mechanism. Lever 11 is held in and returned to lower normal position by spring 11^a. The other end 20 of lever 11 projects below its journal bar 12 and is connected with the key mechanism of the typewriter so that it will be moved by each key when struck. I have illustrated for this purpose a bent rod 20^a, engaging the downwardly projecting arm 20. This rod may have the projection 20^b for operating the carriage escapement and extends to the front of the machine for operation by the usual universal bar extending under the key levers. The engaging faces of arm 20 and rod 20^a are so shaped, as for example, by curving them as shown, that the point of engagement travels from the end of arm 20 toward its pivot bar—thus easing the motion of the frisket at starting and accelerating said motion at the end. Each movement of rod 20^a rocks the lever 11 and thus by the pin 10 gives to the operating pin 6 the reciprocation by which the frisket 1 is operated as above pointed out. When the key is released, the ribbon shift mechanism returns to normal position and leaves the writing again visible.

The guide frame 5 is not secured rigidly in the typewriter machine, but is intended to have a certain movement transversely of

the machine. For this purpose, the frame 5 is provided with studs 22 and 23 which pass through slots 36 and 37 of plate 14 and to which studs are pivotally attached by pivot screws 24 and 25 the upper ends of a pair of levers 26 and 27, which latter have their lower ends pivotally attached to plate 14 by the screws 15 and 16, and thus form a parallel link movement. On pivot screw 24 (Fig. 1) is movably fastened lever arm 28, the end 29 of which is channeled in cross section as shown in Fig. 5 and carries the knob 30, by which the link movement with frame 5 can be reciprocated as far as opening 34 in plate 14, through which the stem 35 of knob 30 is led, will allow it. Stem 35 may be set into different notches 34, I, II, III so that thereby the different colors desired of the colored ribbon 4 (Fig. 4) may be brought into operation. Knob-stem 35 is kept in these notches by the channeled end 29 of lever 28 which is then resting with its inclined surface on the end of spring 38, (Fig. 5) secured on main plate 14 by screw 39. In Figs. 1 and 4 are shown three notches 34, I, II, III showing that either a three colored ribbon may be used or in case of a single colored ribbon the latter may be used on three different paths while passing through the typewriter. Opening 34, Fig. 4, is provided besides with the lateral notch 40. If knob-stem 35 is drawn into the latter, it will be seen that the link movement with the ribbon guide may be drawn to the extreme right whereby hook 9 will be disengaged from pin 10 and drawn up the inclined plate 44 secured on main plate 14 (Fig. 4). Thus the whole ribbon movement is put out of action and locked, whereafter the typewriter may be used for writing direct as in mimeographic work. To prevent hook 9 from becoming disengaged from pin 10 when the latter is not in registry with inclined plate 44, bar 45 (Figs. 2, 4) preferably made integral with main plate 14, is provided against which the back of hook 9 will strike if it is not in registry with the end of inclined plate 44, and should then attempt to move to the extreme right. Arm 28, Fig. 1 is further provided with a downward extension 46 having the notch 47. On pivot screw 16 is pivotally fastened bell-crank 48 carrying on its end near notch 47, a pin 49 (Figs. 1, 2) and forked on its other end 50 (Fig. 1). In frame 13 (Figs. 2, 3) is fulcrumed by pivot 53 a lever 52 which is forked on its lower arm 54 and engages with its other arm 51 in the forked end 50 of bell crank 48 (Figs. 1, 2, 3). In fork 54 of lever 52 moves the disk 56, eccentrically mounted on shaft 55, Fig. 2. Said shaft 55 as shown in Fig. 4 is the usual ribbon shift or drive shaft, being driven by the carriage main spring drum I in its revolution during the letter space movement.

by means of the pawl K, ratchet wheel J, upon which the miter gear P is mounted, which in turn drives miter gear O which is splined upon the shaft 55. Disk 56 in revolving, causes lever 52 and in turn bell-crank 48, to rock, as long as the ribbon shift or feed mechanism of the typewriter is in action. If now in Fig. 1 knob 30 is moved down to the bottom of opening 34, notch 47 10 will engage pin 49 of bell-crank 48 and when the latter rocks thus give the parallel link movement with ribbon guide device 1 a slow reciprocating motion during the operation of the typewriter. The result is that the 15 types of the machine strike the ribbon in a zig-zag line or path, extending over the whole width of the ribbon, thus using in time the whole surface of a single colored ribbon after the latter has run several times 20 its whole length through the machine. Where a bichrome or multichrome (both forms being included by me in the claims as "polychrome"), ribbon is used, the same movement may be given to the ribbon, causing the writing to alternate in color.

In Fig. 4 the invention is shown for convenience mounted in a Victor typewriter, part of the front frame B, B being broken away to show the mechanism. In this figure D is the top-plate of the typewriter, supported on the front and rear frame standards or posts B and C; A is the base; E is the platen; F are the ribbon spools; G their shafts; H beveled pinions on said shafts; I the spring drum for driving the platen carriage and ribbon spools; J and K ratchet and pawl on same; L spring for pawl K; M and N supports for said spring; O bevel pinion splined on shaft 55, and meshing 40 with similar gear P on spring drum I; Q, Q beveled pinions fast on shaft 55 meshing with spool pinions H, H; R a latch engaging notches S on shaft 55, to hold latter in one or other of its longitudinal positions; T 45 the type-bar segment to which plate 14 of the ribbon movement is secured by screws passing through holes X, X, therein; V is a bearing lug for shaft 55, W a stationary guide for the ribbon. It will be seen that 50 by applying screws to the holes X, X the whole ribbon movement may be attached to or removed from the typewriter.

I have described a specific embodiment of the principles of my invention to avoid confusion, but it is to be understood that this embodiment is intended only as an illustration and my invention is not limited to the specific features herein shown and described.

Having thus described my invention, the following is what I claim as new, therein and desire to secure by Letters Patent:

1. A ribbon mechanism comprising means for receiving and discharging the ribbon longitudinally in a generally horizontal di-

rection substantially parallel to the platen, but leading the operative field of the ribbon bodily longitudinally substantially in a vertical plane.

2. A ribbon mechanism comprising means 70 for leading the operative field of the ribbon longitudinally in a vertical direction, and means for moving bodily the operative field of the ribbon substantially in a vertical plane into striking position.

3. A ribbon mechanism comprising means for receiving and discharging the ribbon longitudinally in a general horizontal direction substantially parallel to the platen, but leading the operative field of the ribbon 80 longitudinally in a vertical direction, and means for moving the operative field of the ribbon substantially in a vertical plane into striking position.

4. In a ribbon mechanism, the combination with means for holding the operative field of the ribbon longitudinally vertical; of means for moving the operative field of the ribbon substantially in a vertical plane into striking position.

5. A ribbon mechanism comprising a frisket adapted to hold the operative field of the ribbon longitudinally vertical, a guide frame adapted to admit movement of said frisket in a vertical direction, and means 95 for causing movement of said frisket substantially in a vertical plane.

6. In a ribbon mechanism, the combination with a frisket adapted to hold the operative field of the ribbon longitudinally vertical, and a guide frame permitting vertical movement of said frisket; of an operating pin secured to said frisket, and a lever actuated by the operation of the key and adapted to reciprocate said operating pin and thus 105 move said frisket in vertical direction.

7. In a ribbon mechanism, the combination with a frisket adapted to hold the operative field of the ribbon longitudinally vertical, and a guide frame permitting vertical movement of said frisket; of an operating pin rigidly secured to said frisket and guided in said guide frame, an actuating lever for said operating pin, and means whereby depression of the key rocks said 115 actuating lever.

8. In a ribbon mechanism, the combination with a frisket adapted to hold the operative field of the ribbon longitudinally vertical, a guide frame provided with grooved guide lugs in which said frisket is guided vertically and an operating pin for said frisket rigidly secured at the lower portion of the frisket and guided in said guide frame, said operating pin being provided 120 at its lower end with a hook; of an actuating lever having at one end a pin adapted to engage the hook of said operating pin, and means for rocking said actuating lever in the depression of the key.

9. In a ribbon mechanism, in combination with a frisket adapted to hold the operative field of the ribbon longitudinally vertical, and a guide frame permitting vertical movement of said frisket into and out of operative position; of means for setting said guide frame at laterally variable positions.
10. In a ribbon mechanism, the combination with a frisket adapted to hold the operative field of the ribbon longitudinally vertical, and a guide frame permitting vertical movement of said frisket into and out of operative position; of means for setting said guide frame at laterally variable positions, and means for giving to said frisket a vertical movement.
11. In a ribbon mechanism, the combination with a frisket adapted to hold the operative field of the ribbon longitudinally vertical, and a guide frame permitting vertical movement of said frisket into and out of operative position; of means for setting said guide frame at laterally variable positions, an operating pin adapted when reciprocated to move said frisket vertically, a lever adapted when rocked to reciprocate said operating pin, and means whereby operation of the key rocks said lever.
12. A ribbon mechanism comprising a frisket adapted to hold the operative field of the ribbon longitudinally vertical, and a guide frame permitting vertical movement of said frisket into and out of operative position; of means for operating said frisket, and means for disengaging said operating means.
13. A ribbon mechanism comprising a frisket adapted to hold the operative field of the ribbon longitudinally vertical, and a guide frame permitting vertical movement of said frisket into and out of operative position; of an operating pin guided in said guide frame and provided with a hooked end, an actuating lever having a pin engaging in the hooked end of said operating pin, means whereby actuation of a key rocks said actuating lever, and means for moving said guide frame laterally and thus freeing the operating pin from the actuating lever.
14. In a ribbon mechanism, the combination with a frisket adapted to hold the operative field of the ribbon, and a guide frame permitting vertical movement of said frisket into and out of operative position; of means for setting said guide frame at laterally variable positions.
15. In a ribbon mechanism, the combination with a frisket adapted to hold the operative field of the ribbon, and a guide frame permitting vertical movement of said frisket into and out of operative position; of means for setting said guide frame at laterally variable positions, and means for giving to said frisket a vertical movement.
16. In a ribbon mechanism, the combination with a frisket adapted to hold the operative field of the ribbon, and a guide frame permitting vertical movement of said frisket into and out of operative position; of means for setting said guide frame at laterally variable positions, an operating pin adapted when reciprocated to move said frisket vertically, a lever adapted when rocked to reciprocate said operating pin, and means whereby operation of the key rocks said lever.
17. A ribbon mechanism comprising a frisket adapted to hold the operative field of the ribbon, and a guide frame permitting vertical movement of said frisket into and out of operative position; of an operating pin guided in said guide frame and provided with a hooked end, an actuating lever having a pin engaging in the hooked end of said operating pin, means whereby actuation of a key rocks said actuating lever, and means for moving said guide frame laterally and thus freeing the operating pin from the actuating lever.
18. In a ribbon mechanism, the combination with a frisket adapted to hold the operative field of the ribbon, and a guide frame permitting vertical movement of said frisket into and out of operative position; of a main supporting plate, a pair of parallel links pivotally connected at one end to said guide frame and at the other end to said main supporting plate, and means for moving said guide frame on said parallel links to set the guide frame in laterally variable positions.
19. In a ribbon mechanism, the combination with a frisket adapted to hold the operative field of the ribbon, and a guide frame permitting vertical movement of said frisket into and out of operative position; of a main supporting plate, a pair of parallel links pivotally connecting said guide frame to said main supporting plate, means for moving said guide frame laterally on said parallel links to set the frame at laterally variable positions, and means for moving said frisket vertically.
20. In a ribbon mechanism, the combination with a frisket adapted to hold the operative field of the ribbon, and a guide frame permitting vertical movement of said frisket into and out of operative position; of a main supporting plate, a pair of parallel links pivotally connecting said guide frame to said main supporting plate, means for moving said guide plate on said parallel links to set the guide frame at laterally variable positions, an operating pin adapted when reciprocated to move said frisket vertically, a lever adapted when rocked to reciprocate said operating pin and means whereby operation of a key rocks said lever.
21. A ribbon mechanism comprising a frisket adapted to hold the operative field of

- the ribbon, and a guide frame permitting vertical movement of said frisket into and out of operative position; of a main supporting plate, a pair of parallel links pivotally connecting said guide frame to said main supporting plate, means for operating said frisket and means for moving said guide frame on said parallel links to disengage said operating means.
- 10 22. A ribbon mechanism comprising a frisket adapted to hold the operative field of the ribbon, and a guide frame permitting vertical movement of said frisket into and out of operative position; of an operating pin guided in said guide frame and provided with a hooked end, an actuating lever having a pin engaging in the hooked end of said operating pin, means whereby actuation of a key rocks said actuating lever, a main supporting plate, a pair of parallel links pivotally connecting said guide frame to said main supporting plate, and means for moving said guide frame laterally on said parallel links to free the operating pin from the actuating lever.
- 15 23. In a typewriter, the combination with a polychrome ribbon, a frisket adapted to hold the operative field of said ribbon longitudinally vertical, and a guide frame permitting vertical movement of said frisket into and out of operative position; of a main supporting plate, a pair of parallel links pivotally connecting said guide frame to said main supporting plate, and means for moving said guide frame on said links to set the guide frame at laterally variable positions corresponding to the colors on said polychrome ribbon.
- 20 24. In a typewriter, the combination with a polychrome ribbon, a frisket adapted to hold the operative field of said ribbon longitudinally vertical, and a guide frame permitting vertical movement of said frisket into and out of operative position; of a main supporting plate, parallel links pivotally connecting said guide frame to said plate, means for moving said guide frame on said links to set the guide frame at laterally variable positions corresponding to the colors on said polychrome ribbon and means for giving to said frisket a vertical movement.
- 25 25. In a typewriter, the combination with a polychrome ribbon, a frisket adapted to hold the operative field of said ribbon longitudinally vertical, and a guide frame permitting vertical movement of said frisket into and out of operative position; of a main supporting plate, parallel links pivotally connecting said guide frame to said plate, means for moving said guide frame on said links to set said guide frame at laterally variable positions corresponding to the colors on said polychrome ribbon, an operating pin adapted when reciprocated to move said frisket vertically, a lever adapted when
- 30 35 40 45 50 55 60 65 70 75 80 85 90 95 100 105 110 115 120 125 130
- rocked to reciprocate said operating pin, and means whereby operation of a key rocks said lever.
26. In a typewriter, the combination with a polychrome ribbon, a frisket adapted to hold the operative field of the ribbon longitudinally vertical, and a guide frame permitting vertical movement of said frisket into and out of operative position; of a main supporting plate, parallel links pivotally connecting said guide frame with said main supporting plate, means for operating said frisket, means for moving said guide frame on said links to set the guide frame at laterally variable positions corresponding to the colors on said polychrome ribbon, and means for disengaging said frisket from its operating means.
27. In a typewriter, the combination with a polychrome ribbon, a frisket adapted to hold the operative field of said ribbon longitudinally vertical, and a guide frame permitting vertical movement of said frisket into and out of operative position; of an operating pin guided in said guide frame and provided with a hooked end, an actuating lever having a pin engaging in the hooked end of said operating pin, means whereby actuation of a key rocks said actuating lever, a main supporting plate, parallel links pivotally connecting said guide frame to said plate, and means for moving said guide frame on said parallel links to free said operating pin from said actuating lever.
28. In a typewriter, the combination with a polychrome ribbon; of means for leading the operative field of said ribbon longitudinally in vertical direction and means for moving the operative field of said ribbon bodily transversely in a horizontal direction, the longitudinal axis of said field maintaining the same vertical position.
29. In a typewriter, the combination with a polychrome ribbon; of means for receiving and discharging the ribbon longitudinally in a generally horizontal direction in parallel to the platen, but leading the operative field of the ribbon longitudinally in a vertical direction and means for moving the operative field of said ribbon bodily transversely in a horizontal direction, the longitudinal axis of said field maintaining the same vertical position.
30. In a typewriter the combination with a polychrome ribbon; of means for leading the operative field of the ribbon longitudinally in a vertical direction, means for removing the operative field of said ribbon, transversely in horizontal direction, the longitudinal axis of said field maintaining the same vertical position, and means for bodily moving the operative field of the ribbon substantially in a vertical plane into striking position.

31. In a typewriter the combination with a polychrome ribbon; of means for receiving and discharging said ribbon longitudinally in a generally horizontal direction in part parallel to the platen, but leading the operative field of the ribbon longitudinally in a vertical direction, means for moving the operative field of said ribbon transversely in a horizontal direction, the longitudinal axis of said field maintaining the same vertical position, and means for moving the operative field of said ribbon substantially in a vertical plane into striking position.
32. In a typewriter the combination with a polychrome ribbon, and means for holding the operative field of said ribbon, longitudinally vertical; of means for moving the operative field of the ribbon transversely in a horizontal direction, the longitudinal axis of said field maintaining the same vertical position, and means for moving the operative field of the ribbon substantially in a vertical plane into striking position.
33. In a typewriter the combination with a polychrome ribbon, a frisket adapted to hold the operative field of said ribbon longitudinally vertical and a guide frame adapted to permit movement of said frisket substantially in a vertical plane; of means for operating said frisket and means disconnecting said frisket in its inoperative position from its operating means and means for locking the same when disconnected.
34. In a typewriter, the combination with a ribbon, a frisket adapted to hold the operative field of said ribbon, a guide frame permitting movement of said frisket substantially in a vertical plane into and out of operative position; of means for operating said frisket, means for disconnecting said frisket from its operating means in its inoperative position, and means for locking said frisket against operation when disconnected from its operating means.
35. In a typewriter, the combination with a ribbon, a frisket adapted to hold the operative field of said ribbon, and a guide frame permitting vertical movement of said frisket substantially in a vertical plane into and out of operative position; of an operating pin for said frisket guided in said guide frame and provided with a hooked end, an actuating lever provided with a pin engaging in the hooked end of said operating pin, means whereby actuation of a key rocks said actuating lever, a plate registering with the hooked end of said operating pin, means for moving said guide frame laterally to free the hooked end of said operating pin from the pin on the actuating lever, and moving the same into engagement with said plate to lock the frisket in its inoperative position when disconnected from its operating means, and means preventing such lateral move-
ment of said guide frame when the hooked end of said operating pin is not in registry with said plate.
36. In a typewriter, the combination with a ribbon, a frisket adapted to hold the operative field of said ribbon, a guide frame permitting vertical movement of said frisket into and out of operative position, and means for moving said frisket vertically into and out of operative position; of automatic means for moving said guide frame back and forth laterally during the operation of the typewriter.
37. In a typewriter, the combination with a ribbon, a frisket adapted to hold the operative field of said ribbon and permitting the feeding of the ribbon vertically through the operative field, and a guide frame permitting vertical movement of said frisket into and out of operative position; of means for moving said frisket vertically into and out of operative position, and automatic means for moving said ribbon back and forth laterally in horizontal direction in the operative field during its feeding in vertical direction.
38. In a ribbon mechanism, the combination of ribbon guides, a frisket carrying said guides, means controlled by the printing keys for shifting said frisket to bring the ribbon opposite and away from the printing point, and adjustable means for shifting the frisket laterally of the operative field of the ribbon to bring different longitudinal portions thereof into use.
39. In a ribbon mechanism, the combination of ribbon guides, a frisket carrying said guides, means controlled by the printing keys for shifting said frisket to bring the ribbon opposite and away from the printing point, and adjustable means for shifting the frisket laterally of the operative field of the ribbon to bring different longitudinal portions thereof into use, and means for holding the frisket in such adjustable position.
40. In a ribbon mechanism, the combination of a ribbon guiding mechanism having a frisket moving in a vertical plane guiding the operative field of the ribbon longitudinally vertically and adapted to have a limited lateral movement in the same plane, corresponding to the width of the ribbon, automatic means controlled by the operation of the printing keys for causing said lateral frisket movement during the printing operation, and hand operated means for setting said frisket into and releasing same from the key controlled position.
41. In a ribbon mechanism, the combination of ribbon guides, a frisket carrying said guides, means controlled by the operation of the printing keys for shifting the operative field of the ribbon to and away from operative position, and means also controlled by

the operation of the printing keys for moving said ribbon both longitudinally and laterally across the printing point.

42. In a typewriting machine, the combination of a ribbon normally removed from the printing point; means for feeding the ribbon longitudinally; means for causing the ribbon to cover the printing point during printing operations; means operating automatically to vary the normal position of the printing portion of the ribbon; and means for rendering said last recited means inoperative.

43. In a typewriting machine, the combination of types; a vibratory ribbon carrier; means for giving said ribbon carrier an unvarying extent of movement or throw during printing operations; means for automatically varying the normal position of said ribbon carrier; and means for rendering said last recited means inoperative.

44. In a typewriting machine, the combination of types; a vibratory ribbon carrier; means for giving said ribbon carrier an unvarying extent of movement or throw during printing operations; means operating automatically to progressively vary the normal position of the ribbon carrier during the vibratory movements thereof; and means for rendering said last recited means inoperative.

45. In a typewriting machine, a ribbon vibrating mechanism for a ribbon normally removed from the printing point comprising means for causing the ribbon to cover the printing point during printing operations, means operating automatically to vary the normal position of the printing portion of the ribbon, and means for rendering said last recited means inoperative, said mechanism also including hand operated means for positioning the ribbon at will normally so that it may be moved to an unvarying predetermined point by said first recited means.

46. In a typewriting machine, the combination with types, of a ribbon vibrating mechanism for a ribbon normally removed from the printing point comprising a vibratory carrier, means for giving said carrier unvarying extents of movement at printing operation, means operating automatically to progressively vary the normal position of said carrier, during the vibratory movements thereof, and means for rendering said last recited means inoperative, said means also including hand operated means for setting said carrier in any one of a plurality of predetermined normal positions to present at will a predetermined widthwise portion of the ribbon to the types at printing operation.

47. A ribbon mechanism comprising means for receiving and discharging the ribbon

longitudinally in a generally horizontal direction substantially parallel to the platen, but moving the operative field of the ribbon bodily longitudinally substantially in a vertical plane.

48. In a typewriting machine, the combination with a platen, of ribbon mechanism including a vibratory carrier which guides the printing portion of the ribbon crosswise of the direction of the lines of print, means for moving the carrier to cause the ribbon to cover the printing point, and means for automatically varying the direction of the line of vibratory movement of the carrier.

49. In a typewriting machine, the combination with a platen, of ribbon mechanism including a vibratory carrier which guides the printing portion of the ribbon crosswise of the direction of the lines of print, means for moving the carrier to cause the ribbon to cover the printing point, and means operating automatically to vary the direction of the line of vibratory movement of the carrier to bring widthwise portions of the printing portion of the ribbon opposite the printing point when the moving means operates.

50. In a typewriting machine, the combination with a platen, of a vibratory ribbon carrier which maintains the printing portion of the ribbon in a direction crosswise of the lines of print, means automatically operating to vary the normal position of said carrier in a direction lengthwise of the lines of print, and means for actuating said carrier at printing operations.

51. In a typewriting machine, the combination with a platen, of a vibratory ribbon carrier which maintains the printing portion of the ribbon in a direction crosswise of the lines of print, means operative either automatically or by hand to vary the normal position of said carrier in a direction lengthwise of the lines of print, and means for actuating said carrier at printing operations.

52. In a typewriting machine, the combination with a platen, of a vibratory ribbon carrier which maintains the printing portion of the ribbon in a direction crosswise of the lines of print, means automatically operative to vary the position of said carrier in a direction lengthwise of the lines of print, and independent means for actuating said carrier at printing operations.

53. In a ribbon mechanism, the combination of a vibratory ribbon carrier, a guide for said carrier and on which said carrier is movable, means automatically operative to vary the position of said guide, and means for actuating said carrier.

54. In a ribbon mechanism, the combination of a vibratory ribbon carrier, a guide

for said carrier and on which said carrier is movable, means operative either automatically or by hand to vary the position of said guide, and means for actuating said carrier.

55. In a ribbon mechanism, the combination of a vibratory ribbon carrier, a guide for said carrier and on which said carrier is movable, means operative automatically for varying the position of said guide to vary the normal position of said carrier, and means for actuating said carrier at printing operation.

56. In a ribbon mechanism, the combination of a vibratory ribbon carrier, a guide for said carrier and on which said carrier is movable, means operative either automatically or by hand for varying the position of said guide to vary the normal position of said carrier, and means for actuating said carrier at printing operation.

57. In a typewriting machine, the combination with a cylindrical platen, of a vibratory ribbon carrier which maintains the printing portion of the ribbon substantially at right angles to the lines of print, a guide for said carrier, means operative automatically to adjust said guide in the general direction of the length of the platen, and means for actuating said ribbon carrier at printing operation.

58. In a typewriting machine, the combination with a cylindrical platen, of a vibratory ribbon carrier which maintains the printing portion of the ribbon substantially at right angles to the lines of print, a guide for said carrier, means operative either automatically or by hand to adjust said guide in the general direction of the length of the platen, and means for actuating said ribbon carrier at printing operation.

59. In a front-strike typewriting machine, the combination with a horizontally arranged platen, of a vertically disposed vibratory ribbon carrier provided with devices for maintaining the printing portion of the ribbon in a direction crosswise of the lines of print, a guide for said carrier, and means operating automatically to vary the normal position of said guide in a direction lengthwise of the lines of print.

60. In a front-strike typewriting machine, the combination with a horizontally arranged platen, of a vertically disposed vibratory ribbon carrier provided with devices for maintaining the printing portion of the ribbon in a direction crosswise of the lines of print, a guide for said carrier, and means for varying the normal position of said guide in a direction lengthwise of the lines of print, said means being operative either automatically or by hand at will.

61. In front-strike typewriting machine, the combination with a horizontally ar-

ranged platen, of a vertically disposed vibratory ribbon carrier provided with devices for maintaining the printing portion of the ribbon in a direction crosswise of the lines of print, a guide for said carrier pivotally supported below the platen and extending upward toward the platen, and means operating automatically to swing said guide substantially lengthwise of the platen.

62. In a typewriting machine, a ribbon changing mechanism comprising a shiftable guide, means operating automatically to shift said guide, a vibratory ribbon carrier arranged on said guide and means for vibrating said carrier.

63. In a typewriting machine, the combination of a horizontally arranged platen, ribbon spools having fixed paths of rotation, a ribbon carrier normally maintaining the ribbon away from the printing point, and means for automatically moving the ribbon carrier substantially lengthwise of the platen.

64. In a typewriting machine, the combination of a horizontally arranged platen, ribbon spools having fixed paths of rotation, a ribbon carrier normally maintaining the ribbon away from the printing point, means for automatically moving the ribbon carrier substantially lengthwise of the platen, and independent means for moving the carrier to the printing point at printing operation.

65. In a typewriting machine, the combination with a platen, of ribbon mechanism which guides the printing portion of the ribbon crosswise of the direction of the lines of print and which includes means for moving the ribbon at printing operations to and fro to cover and uncover the printing point, and alternative means for varying the last recited means.

66. In a typewriting machine, the combination with a platen, of ribbon mechanism which guides the printing portion of the ribbon crosswise of the direction of the lines of print and which includes means for moving the ribbon at printing operations to and fro to cover and uncover the printing point, and alternative means for varying the last recited means, one of said alternative means being hand controlled and the other being automatic.

67. In a typewriting machine, the combination with printing instrumentalities and a horizontal platen, or ribbon spools at the sides of the machine, a vibratory ribbon carrier provided with devices which maintain the printing portion of the ribbon substantially at right angles to the lines of print, a guide for said carrier, means for adjusting said guide in the general direction of the length of the platen and maintaining it set in adjusted position, and means for actuating said ribbon carrier at printing operation.

68. In a front-strike typewriting machine, the combination with printing instrumentalities and a horizontally arranged platen, of an upright vibratory ribbon carrier having means for maintaining the printing portion of the ribbon at substantially right angles to the lines of print, means for setting said carrier in one or another of a plurality of normal positions substantially lengthwise of the lines of print, and means for actuating said carrier at printing operation. 65
69. In a front-strike typewriting machine, the combination with printing instrumentalities and a horizontally arranged platen, of ribbon spools at the sides of the machine, a vertically disposed vibratory ribbon carrier provided with devices for maintaining the printing portion of the ribbon in a direction crosswise of the lines of print, a guide 70 for said carrier, and means for varying the normal position of said guide in a direction lengthwise of the lines of print and for holding the guide set in adjusted positions. 75
70. In a front-strike typewriting machine, the combination with printing instrumentalities and a horizontally arranged platen, of a vertically disposed vibratory ribbon carrier provided with devices for maintaining the printing portion of the ribbon in a direction crosswise of the line of print, a guide 80 for said carrier, and means for varying the normal position of said guide in a direction lengthwise of the lines of print, said last recited means comprising a handle or finger 85 piece operative from the front of the machine and connections between said handle and said guide. 90
71. In a typewriting machine, the combination with a platen, and printing instrumentalities, of a vibratory ribbon carrier, a movable guide for said carrier, means for moving said guide to vary its normal position, said means comprising a hand-controlled arm and connections between said 95 arm and said guide, and stop means for limiting the movements of said arm. 100
72. In a typewriting machine, the combination of a vibratory ribbon carrier comprising a head provided with turning devices, which maintain the printing portion of the ribbon in a direction crosswise of the lines of print, a support for said carrier provided with a guide on which said carrier is slidable, a pivot on which said support is adjustable substantially lengthwise of the lines of print, and means operating automatically to adjust said support. 105
73. In a typewriting machine, the combination with a platen and printing instrumentalities, of ribbon mechanism which guides the printing portion of the ribbon crosswise of the direction of the lines of print and which includes means for moving the ribbon at printing operations to and fro 110 to cover and uncover the printing point, and alternative means for varying the last recited means, one of said alternative means being hand controlled and the other being automatic, said hand controlled means being adjustable to cause the printing portion of the ribbon to be moved in any one of a plurality of predetermined paths. 115
74. In a typewriting machine, the combination of a platen, printing instrumentalities; a vibratory ribbon carrier having turning devices arranged obliquely to the printing line on the platen, the printing portion of the ribbon passing from one turning device to the other crosswise of the direction of the line of print, and means for automatically moving the ribbon carrier to cause the ribbon to cover the printing point. 120
75. In a typewriting machine, the combination with a platen and printing instrumentalities, of ribbon mechanism including a vibratory carrier provided with means which guides the printing portion of the ribbon crosswise of the direction of the lines of print, and so that the printing portion of the ribbon is laterally diverted from the general direction or run of the ribbon, means for moving the carrier to cause the ribbon to cover the printing point, and means for varying the path in which the carrier moves. 125
76. In a typewriting machine, the combination with a platen and printing instrumentalities, of ribbon mechanism including a vibratory carrier provided with means which guides the printing portion of the ribbon crosswise of the direction of the lines of print, and so that the printing portion of the ribbon is laterally diverted from the general direction or run of the ribbon, moving means for moving the carrier to cause the ribbon to cover the printing point, and means for varying the path of movement of the carrier to bring different widthwise portions of the printing portion of the ribbon opposite the printing point when the moving means operates. 130
77. In a typewriting machine, the combination with a platen and printing instrumentalities, of ribbon mechanism including a vibratory carrier provided with means which guides the printing portion of the ribbon crosswise of the direction of the lines of print, and so that the printing portion of the ribbon is laterally diverted from the general direction or run of the ribbon, moving means for moving the carrier to cause the ribbon to cover the printing point, and means for varying the path of movement of the carrier to bring different widthwise portions of the printing portion of the ribbon opposite the printing point when the moving means operates, said last named means being operative by hand. 135

78. In a typewriting machine, the combination of a platen, ribbon spools, ribbon feeding mechanism, a vibratory ribbon carrier carrying guiding means by which the printing portion of the ribbon is guided crosswise of direction of the line of print substantially at right angles to the direction in which the ribbon feeds off one ribbon spool and to the direction in which the ribbon feeds on the other ribbon spool, and means for actuating the vibratory carrier at printing operation.

79. In a typewriting machine, the combination of a platen, ribbon spools arranged to rotate at the sides of the machine, and so that the ribbon feeds longitudinally in a generally horizontal direction lengthwise of the platen and toward and away from the middle of the machine, and a vibratory ribbon carrier arranged substantially at the middle of the machine and provided with means for causing the ribbon to travel longitudinally in a direction crosswise of the horizontal direction first above described.

80. In a typewriting machine, the combination of a platen, ribbon spools at the sides of the machine, ribbon feeding mechanism, a vibratory ribbon carrier provided with oblique turning bars for guiding the printing portion of the ribbon substantially at right angles to a line connecting the ribbon spools, and so that the printing portion of the ribbon is diverted laterally from the direction of the general run of the ribbon and feeds longitudinally crosswise of the general run, and means for actuating said carrier at printing operation.

81. In a typewriting machine, the combination of a platen, ribbon spools at the sides of the machine, ribbon feeding mechanism, a vibratory ribbon carrier provided with oblique turning devices for guiding the printing portion of the ribbon substantially at right angles to the direction in which the ribbon feeds off one ribbon spool and to the direction in which the ribbon feeds on the other ribbon spool, and so that the printing portion of the ribbon is diverted laterally from the direction of the general run of the ribbon and feeds longitudinally crosswise of the general run, and means for actuating said carrier at printing operation.

82. In a typewriting machine, the combination of a platen, ribbon spools at the sides of the machine, ribbon feeding mechanism, a vibratory ribbon carrier provided with oblique turning devices for changing the direction of the ribbon between the spools and guiding the printing portion of the ribbon transversely of the printing line, and so that the printing portion of the ribbon is diverted laterally from the direction of the general run of the ribbon and feeds longitudinally crosswise of the general run, and means for actuating said carrier.

83. In a typewriting machine, the combination with printing instrumentalities and a platen, of a vibratory ribbon carrier provided with a ribbon guide which maintains the printing portion of the ribbon in a direction crosswise of the lines of print, and so that the printing portion of the ribbon is diverted laterally from the direction of the general run of the ribbon and feeds longitudinally crosswise of the general run, means for varying the position of said carrier in a direction lengthwise of the lines of print, and means for actuating said carrier at printing operation.

84. In a typewriting machine, the combination with printing instrumentalities and a platen, of a vibratory ribbon carrier provided with a ribbon guide, which maintains the printing portion of the ribbon in a direction crosswise of the lines of print, and so that the printing portion of the ribbon is diverted laterally from the direction of the general run of the ribbon and feeds longitudinally crosswise of the general run, means for moving said carrier to vary the normal position of the printing portion of the ribbon, and means for actuating said carrier at printing operation.

85. In a ribbon mechanism, the combination of a vibratory ribbon carrier, a guide for said carrier and on which said carrier is movable, means independent of the operation of the machine for varying the position of said guide, and means for actuating said carrier.

86. In a ribbon mechanism, the combination of a vibratory ribbon carrier, a guide for said carrier and on which said carrier is movable, means independent of the operation of the machine for varying the position of said guide to vary the normal position of said carrier, and means for actuating said carrier at printing operation.

87. In a ribbon mechanism, the combination of a vibratory ribbon carrier, a guide on which said carrier is movable, hand-controlled means independent of the operation of the machine for varying the normal position of said guide, and means for actuating said carrier at printing operation.

88. In a typewriting machine, the combination with printing instrumentalities and a platen, of a vibratory ribbon carrier provided with devices for maintaining the printing portion of the ribbon in a direction crosswise of the lines of print, a guide for said carrier pivotally supported, and means for swinging said guide on its pivot.

89. In a front-strike typewriting machine, the combination with printing instrumentalities and a horizontally arranged platen, of a vertically disposed vibratory ribbon carrier provided with devices for maintaining the printing portion of the ribbon in a direction crosswise of the lines of print,

a guide for said carrier pivotally supported below the platen and extending upwardly toward the platen, and hand-operated means for swinging said guide on its pivot lengthwise of the platen.

90. In a typewriting machine, the combination with printing instrumentalities, of a vibratory ribbon carrier comprising a head provided with turning devices which maintain the printing portion of the ribbon in a direction crosswise of the lines of print, a support for said carrier provided with guides on which said carrier is slideable, a pivot on which said support is adjustable substantially lengthwise of the lines of print, and hand-controlled means for adjusting said support.

91. In a typewriting machine, the combination with a platen and printing instrumentalities, of a vibratory ribbon carrier, a movable guide for said carrier, means independent of the operation of the machine for moving said guide to vary its normal position, said means comprising a hand-controlled arm and connections between said arm and said guide, and stop means for limiting the movements of said arm.

92. In a typewriting machine, the combination with a platen and printing instrumentalities, of a vibratory ribbon carrier, a movable guide for said carrier, means independent of the operation of the machine for moving said guide to vary its normal position, said means comprising a hand-controlled arm and connections between said arm and said guide, stop means for limiting the movements of said arm, and indicating devices coöperative with said arm.

93. In a typewriting machine, a ribbon field - changing mechanism comprising a shiftable guide on which a vibratory ribbon carrier is arranged to move, and means for shifting said guide independently of the operation of the machine.

94. In a ribbon mechanism for typewriters, a ribbon carrier for the operative or printing portion of the ribbon, guides on said carrier for holding the operative or printing portion of the ribbon crosswise of the printing line and leading the ribbon to and from said printing portion longitudinally of the printing line, one of said guides being inclined to the plane of the printing portion to turn the longitudinally directed portion of the ribbon edgewise to the work.

95. In a ribbon mechanism for typewriters, a carrier for the printing portion of the ribbon, angularly disposed guides on said carrier through which the ribbon passes from and to the sides of the machine, said guides deflecting and holding the printing portion of the ribbon between them substantially at right angles to the portions

passing to the sides of the machine, one of said guides being inclined toward the front 65 of the machine to present the ribbon edgewise to the operator as it passes to or from the side of the machine.

96. In a ribbon mechanism for visible writing typewriting machines, the combination with means for feeding the ribbon longitudinally of the platen, of a ribbon support for the operative field of the ribbon, ribbon guiding members on said support, said guiding members angularly disposed to the longitudinal field of the ribbon, said guiding members being situated one above the other in a vertical direction, the upper guiding member being deflected away from the platen.

97. In a visible writing typewriting machine, the combination of a frisket for carrying the printing field of the ribbon, means for giving the frisket a rectilinear up and down movement, a guide for guiding the 85 frisket in said movement and means for moving said guide laterally with respect to the frisket movement while maintaining the rectilinear movement of the frisket in all positions of the guide.

98. In a visible writing typewriting machine, the combination of a frisket for carrying the printing field of the ribbon, means for giving said frisket a rectilinear movement to and from the printing point, a pivotally supported guide for guiding the frisket in its rectilinear movement and means for moving said frisket guide laterally with respect to the frisket movement while maintaining the rectilinear movements 100 of the frisket parallel in all positions of said guide.

99. In a visible writing typewriting machine, the combination with a frisket for carrying the printing field of the ribbon, 105 means for shifting said frisket into a plurality of positions to present different widthwise portions of the ribbon to the printing point, means for moving the frisket toward and from the printing point, and means for maintaining the paths of the frisket toward and from the printing point parallel in said several positions.

100. In a visible writing typewriting machine, the combination with a frisket for carrying the printing field of the ribbon, a 115 guide frame for said frisket, a parallel-link movement on which said guide-frame is supported, and means for moving said guide-frame and frisket laterally to present 102 different widthwise portions of the ribbon to the type.
